DESIGN FOR A COMBINATION WOODEN SAND MOLD AND SHOVEL

Kay Bojesen, Copenhagen, Denmark, assignor
to Frederik Lunning, Inc., New York, N. Y.

Application September 21, 1939, Serial No. 87,315

Term of patent 3½ years

To all whom it may concern:

Be it known that I, Kay Bojesen, a subject of the Kingdom of Denmark, residing at Copenhagen, Denmark, have invented a new, original, and ornamental Design for a Combination Wooden Sand Mold and Shovel, of which the following is a specification, reference being had to the accompanying drawing, forming part thereof, wherein—

Figure 1 is a perspective view of the assem-

bled combination wooden sand mold and shovel; Fig. 2 is a perspective view of the sand mold, and Fig. 3 is a perspective view of the shovel shown in Fig. 1, looking at the bottom of the shovel.

I claim:

The ornamental design for a combination wooden sand mold and shovel, substantially as shown.

KAY BOJESEN.
